UNITED STATES PATENT OFFICE.

HANS P. JUERGENS, OF CHICAGO, ILLINOIS.

DESIGN FOR A BADGE OR BUTTON.

42,085.

Specification for Design.

Patented Jan. 9, 1912.

Application filed September 11, 1911. Serial No. 648,774. Term of patent 14 years.

To all whom it may concern:

Be it known that I, HANS P. JUERGENS, citizen of the United States, residing at Chicago, in the county of Cook and State of Illinois, have invented a new, original, and ornamental Design for a Badge or Button, of which the following is a specification, reference being had to the accompanying drawing, forming a part hereof.

This invention has for its object to provide a novel and ornamental design for a badge or button.

The accompanying drawing illustrating my design shows the face of a badge or button embodying the same.

I claim:

The ornamental design for a badge or button as shown.

HANS P. JUERGENS.
